US0D1054776S

(12) **United States Design Patent** (10) **Patent No.:** **US D1,054,776 S**
(45) **Date of Patent:** **** Dec. 24, 2024**

(54) **ROUND PAN**

(71) Applicant: **Ungar Automation Technology (Nantong) Co., Ltd.**, Nantong (CN)

(72) Inventor: **Christoph Ing. Ungar**, Nantong (CN)

(**) Term: **15 Years**

(21) Appl. No.: **29/789,717**

(22) Filed: **Oct. 14, 2021**

(30) **Foreign Application Priority Data**

Apr. 16, 2021 (CN) 202130219307.1

(51) **LOC (14) Cl.** **07-02**

(52) **U.S. Cl.**

USPC **D7/359**

(58) **Field of Classification Search**

(57) **CLAIM**

The ornamental design for a round pan, as shown and described.

DESCRIPTION

FIG. 1 is a front view of a round pan showing my new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view of the round pan thereof.

The broken lines shown in the drawings depict portions of the round pan in which the design is embodied that form no part of the claimed design.

1 Claim, 7 Drawing Sheets
